C. H. RIETH.
IMPLEMENT HOLDER.
APPLICATION FILED DEC. 8, 1919.

1,349,223.

Patented Aug. 10, 1920.

Inventor

Charles H. Rieth

By *J. H. Germar, Atty.*

UNITED STATES PATENT OFFICE.

CHARLES H. RIETH, OF ST. LOUIS, MISSOURI.

IMPLEMENT-HANDLE.

1,349,223.

Specification of Letters Patent.

Patented Aug. 10, 1920.

Application filed December 8, 1919. Serial No. 343,209.

To all whom it may concern:

Be it known that I, CHARLES H. RIETH, a citizen of the United States, residing at St. Louis, Missouri, have invented a certain 5 new and useful Improvement in Implement- Handles, of which the following is a full, clear, and exact description, such as will enable others skilled in the art to which it appertains to make and use the same, refer- 10 ence being had to the accompanying drawings, forming part of this specification.

My invention relates to new and useful improvements in handles for implements such as shovels, spades, axes, and the like, 15 the principal object of my invention being to provide a relatively simple, inexpensive, strong, and durable composite handle, that is, a handle composed of a plurality of pieces of material assembled and secured to each 20 other so as to provide practically a one-piece structure.

Heretofore, handles of implements such as shovels, spades, axes, and the like have been formed from a single piece of material 25 and to meet the trade requirements this material must be straight grained and free from defects. At present there is an increasing scarcity of wood suitable for the manufacture of implement handles of the 30 type to which my invention relates, and it is one of the purposes of my invention to meet these conditions and provide a handle which, by virtue of its construction, conserves the supply of suitable wood, such re- 35 sult being attained by constructing a handle from relatively small strips and pieces of material, which, to a large extent, is now considered waste material.

My invention further contemplates sim- 40 plifying the process and cheapening the cost of manufacture of implement handles, particularly those that are provided with an opening and a transversely disposed hand grasp at the rear or upper end.

My invention is effective in eliminating 45 the waste of a large amount of material which, under the present methods of manufacturing handles, is cut away during the manufacture of handles having widened end 50 portions, and, in addition, the handles constructed in accordance with my invention are much more uniform in quality than the ordinary one-piece handles and there is very little, if any, loss of product during the 55 manufacture.

With the foregoing and other objects in

view, my invention consists in certain novel features of construction and arrangement of parts, hereinafter more fully described and claimed, and illustrated in the accompanying drawings, in which—

Figure 1 is an elevational view of an im- 60 plement handle of my improved construction, said handle being of the type generally used on shovels, spades, and certain va- 65

Fig. 2 is a cross section taken approxi- mately on the line 2—2 of Fig. 1.

Fig. 3 is a cross section taken approxi- 70 mately on the line 3—3 of Fig. 1.

Fig. 4 is a cross section taken approxi- 75 mately on the line 4—4 of Fig. 1.

Fig. 5 is an elevational view of a handle 80 constructed in accordance with my invention and which is adapted to be applied to an ax head.

Fig. 6 is an enlarged section taken ap- 85 proximately on the line 6—6 of Fig. 5.

Fig. 7 is a perspective view of the end por- 90 tion of a handle constructed in accordance with my invention and showing a modified form of the hand hold or grip.

Fig. 8 is a perspective view of a baseball 95 bat constructed in accordance with my in- vention.

It will be understood that the handles of shovels, spades and certain types of forks are usually formed of a relatively straight shank or body portion, the lower or forward end thereof being adapted for in- 100 sertion into a socket on the body of the spade or shovel and the opposite end of said handle being widened and provided with a transversely disposed hand grasp immedi- ately in front of which is an opening for the accommodation of the fingers and thumb on the hand of the user of the implement.

Heretofore handles of this type have been constructed from a single piece of material and the formation of the widened rear or 105 upper end of the opening therein involves considerable time, labor and consequent ex- pense. Further, the strips cut away from the sides of the straight shaft or body por- tion of the handle below or in front of the widened rear or upper end is waste material. I propose to effect a saving of this waste material and eliminate the time, labor and expense incident to the formation of the widened rear or upper end of the handle 110 and the opening therein by constructing the main body portion or shank of the han-

dle from a pair of straight grained wooden strips 10 which are preferably half-round in cross section through their length, one of said strips being provided on its inner 5 straight face with a longitudinally disposed rib 11 and the opposite strip being provided on its inner straight face with a longitudinally disposed groove 12. These strips throughout the greater portion of their 10 length are fitted together with their straight inner faces in contact with each other, with the rib 11 occupying the groove 12, and said parts being secured to each other by a suitable adhesive such as water-proof glue, 15 the same being applied to the flat inner faces and the surfaces of the rib and groove before the parts are assembled.

The rear or upper ends of the strips or members 10 are separated and bent outwardly away from each other to form diverging portions 13 and disposed between these diverging portions is a substantially triangular spreader block 14 that is provided on one of its straight side faces with a 25 groove 15 that is adapted to receive a portion of the rib 11 and the opposite side face being provided with a rib 16 which occupies a corresponding portion of the groove 12. This spreader block is secured to the 30 diverging portions 13 of the strips 10 by means of a suitable adhesive such as water-proof glue, the same being applied to the contacting faces of the parts before they are assembled and if desired, transversely 35 disposed pins or elongated rivets such as 17 may be used as additional securing means, such pins or rivets extending through the spreader block and the diverging portions of the strips 10.

40 The ends of the diverging portions 13 of the strips extend a short distance beyond the base of the triangular spreader block 14 and interposed between said ends is a solid cylindrical member 18, preferably formed 45 of straight grained wood. This member is adapted to be grasped by the hand of the user of the implement and the opening 19 between said member and the base of the spreader block 14 accommodates the fingers 50 and thumb of the user's hand. One end of this hand grasp is provided with a groove 20 which accommodates the end portions of the rib 11 in one of the strips and the other end of the hand grasp is provided with a 55 rib 21 that occupies the end portion of the groove 12. This hand grasp is secured to the ends of the strips 10 by a suitable adhesive, preferably water-proof glue, and as a further means of securing the parts firmly 60 together a pin or rivet such as 22 passes axially through said hand grasp and through the end portions of the strips 10. (See Fig. 2.)

Obviously the strips 10 are capable of being easily and cheaply produced and they

can be manufactured with practically no waste. The spreader blocks 14 are comparatively simple and are capable of being cheaply produced inasmuch as it is not necessary for them to be constructed from 70 straight grained or high grade material. The hand grasp members 18 are capable of being easily and cheaply produced from strips of wood of any suitable length and after being properly shaped they can be 75 cut to proper length and their ends provided with the tongues and grooves so that they will combine readily with the end portions of the strips 10.

The hand grasp portion of the implement 80 handle that is constructed in a single piece can be very easily broken inasmuch as the grain of the wood in said hand grasp portion is disposed substantially at right angles 85 to the axis of said hand grasp, but in a handle of my improved construction the possibility of breakage of the hand grasp portion is minimized by virtue of the fact that the grain of the wood runs lengthwise of the member or substantially at right angles to 90 the grain of the wood in the strips 10.

In Fig. 5 I have shown a handle constructed in accordance with my invention and which is particularly adapted to be used on an ax head, said handle being composed of a 95 pair of strips 23 of straight grained wood, the main body portions of which are glued together and there being a longitudinally disposed tongue and groove joint between said strips. The forward or lower ends of 100 the strips of this handle are spaced apart and positioned therein and glued together is an elongated substantially wedge-shaped 105 filler block 24, the edges of which are glued and connected to the inner faces of the adjacent portions of the strips 23 and interlocked therewith by means of the tongue 110 and groove connections. The rear or upper end of this form of handle may be provided with a metal socket such as 25 to prevent the hand from slipping off the end of the handle, or, if desired, the rear ends of the strips 23 may be spread apart for a short 115 distance and a wedge such as 26 inserted between said separated ends, said wedge being substantially wider than the strips 23 so as to form a knob on the rear end of the handle.

In Fig. 8 I have illustrated a baseball bat constructed in accordance with my invention, this particular construction comprising 120 a pair of elongated tapered members 27 which are substantially half-round in cross section, and an elongated wedge-shaped strip of wood 27^a, the latter being interposed between the members 27 and the contacting faces of the parts being provided with tongue and groove joints glued together.

Handles of my improved construction 125 are capable of being easily and cheaply 130

manufactured, are strong, substantial, and durable, have the necessary resiliency, and by virtue of their construction can be produced from considerably less material than 5 is required in the manufacture of the similar types of handles now in general use.

It will be readily understood that minor changes in the size, form and construction of the various parts of my improved handle 10 can be made and substituted for those herein shown and described, without departing from the spirit of my invention, the scope of which is set forth in the appended claims.

15 I claim:

1. As a new article of manufacture, an implement handle comprising a pair of straight grained wooden strips connected to each other by a glue joint, said strips being 20 spread apart at one end to form diverging end portions, and a wedge block inserted between said diverging end portions.

2. As a new article of manufacture, an implement handle comprising a pair of 25 straight grained wooden strips connected to each other by a glue joint, said strips being spread apart at one end to form diverging end portions, a wedge block inserted between said diverging end portions, and a 30 hand-grasp member arranged between and secured to the ends of the diverging portions of said strips and spaced apart from the spacing block.

3. As a new article of manufacture, an 35 implement handle comprising a pair of straight grained wooden strips connected to each other by a glue joint and a tongue and groove connection, said strips being spread apart at one end to form diverging end portions, and a wedge block inserted between 40 said diverging end portions.

4. As a new article of manufacture, an implement handle comprising a pair of straight grained wooden strips connected to 45 each other by a glue joint, said strips being spread apart at one end to form diverging end portions, a wedge block inserted between said diverging end portions, and tongue and groove connections between the 50 edges of said wedge block and said diverging end portions.

5. As a new article of manufacture, an implement handle comprising a pair of straight grained wooden strips, the main body portions of which are directly connected to each other, the rear end portions of said strips being spread apart, and a hand-grasp member arranged between the ends of said diverging portions, and there being tongue and groove joints between the 60 ends of said member and the diverging end portions of said strips. 55

6. As a new article of manufacture, an implement handle comprising a pair of straight grained wooden strips secured to 65 each other by an adhesive, and there being a tongue and groove connection between the engaging faces of said strips, said strips being spread apart at one end to form diverging end portions, a wedge block inserted between said diverging end portions and secured to said strips by an adhesive, and there being tongue and groove joints between the engaging faces of said wedge 70 block and diverging portions. 75

7. As a new article of manufacture, an implement handle comprising a pair of straight grained wooden strips secured to each other throughout the greater portion 80 of their length, said strips being spread apart at one end to form diverging end portions, a wedge block positioned between and secured to said diverging end portions, and a hand-grasp member arranged between and secured to the end of said diverging 85 portions and spaced apart from said block.

8. As a new article of manufacture, an implement handle comprising a pair of straight grained wooden strips connected to each other throughout the greater portion 90 of their length, said strips being spread apart at one end to form diverging portions, a spreader block, and a hand-grasp member positioned between said diverging end portions, and there being tongue and groove 95 connections between said strips, between the edges of the spreader blocks and said strips, and between the ends of the hand-grasp member and said strips.

In testimony whereof I hereunto affix my 100 signature this 5th day of December, 1919.

CHARLES H. RIETH.
